UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PICK AND PICK MOTION FOR BOX LOOMS.

Application filed April 23, 1926. Serial No. 104,186.

This invention relates to improvements in multiplier devices for box motions of looms and it is the general object of the invention to provide a simple form of device for use in connection with looms weaving crepe and other fabrics requiring two picks to be laid by one shuttle to be followed by two picks from another shuttle.

The usual form of box motion of the type to which my invention relates can be used in connection with the ordinary multiplier when it is desired to count a comparatively large number of picks which are laid by any one shuttle, the multiplier chain under these conditions being given a movement for every second pick where there is a single box on one end of the loom and the box chain remaining at rest until the multiplier chain has made a complete revolution, at which time a return indication is given to the box chain and the latter moves forward one space. If the color is still to remain active the next bar of the pattern chain will be the same as the one which first started the multiplier chain, the number of picks taken care of by the multiplier being double the product of the multiplier chain links by the pattern chain bars of the same layout as originally called the multiplier chain.

In certain kinds of fabrics, such as crepe for instance, it is desirable to lay two picks from one shuttle and then two picks from another, the shuttles alternating in pairs of picks for a given length of time, after which a variegated pattern can be woven. Multipliers of the present form cannot be used for weaving a block of color formed of alternate pairs of picks from different shuttles because the multiplier chain will ordinarily move between movements of the pattern chain, and where the pattern chain must move every two picks, the multiplier chain does not get a chance to operate. For this reason it has heretofore been necessary, in building the pattern chain for any repeat which has a crepe or a similar portion, to provide one chain bar for each pair of picks of crepe. For instance, if a repeat is 100 picks long and 40 of these are for crepe and the other 60 for some vari-colored pattern, the pattern chain will contain 50 bars, remembering that one bar suffices for two picks, 20 of the bars being used for that part

of the pattern calling for crepe and the other 30 bars being for the vari-colored part of the pattern, there being 10 bars of one kind and 10 of another for the crepe and the bars being alternated.

It is an important object of my invention to provide a box motion which will permit a multiplier chain to be used instead of the section of box chain corresponding to the 40 picks assumed above, my invention reducing the pattern chain from 50 to 31 bars and employing a multiplier chain of 20 bars to be called by the 31st bar of the pattern chain. A saving is effected in this way because of the fact that the pattern chain may be four spaces or more wide whereas the multiplier chain will be only one space wide.

The usual form of Crompton box motion employs a master gear on the bottom shaft rotating every second pick of the loom. The master gear will have one segment for each pair of shuttle boxes and each segment will cooperate with one pinion through the rotation of which the box lever is either raised or lowered. Each pinion has diametrically opposite slots in which slide the starting teeth, said teeth being in different planes so that but one of them can be acted upon by the segment during any movement of the pinion. If the box lever is to be changed and maintained in its new position, the tooth which was out of the plane of the segment will be moved toward the latter so that as it approaches the pinion the leading tooth of the segment will engage the starting sliding tooth and give the pinion a half revolution. The starting tooth will then be on the side of the pinion opposite the segment and will not be in position to be again acted upon by the segment when the latter makes its next rotation. The box lever will therefore remain in its new position because of the fact that one of the starting sliding teeth is out of the plane of the segment and the other tooth in such position that it cannot be reached by the segment.

My invention consists of an auxiliary starting tooth normally out of the plane of the segment but slideable into the path thereof so that when weaving crepe there will be two starting teeth in the plane of the segment one of which will always be in the path

of the leading tooth of the segment. By this construction the pinion, and hence the boxes, will be moved every time the segment completes a rotation without requiring a 5 change of the pattern chain inasmuch as the regular and auxiliary starting teeth remain the same with respect to the pinion. It is a still further object of my invention to provide a box motion and a pattern mechanism 10 wherein two pattern levers controlled independently of each other by the pattern chain may both control the same pinion.

I have chosen to illustrate my invention in connection with the well-known form of 15 Crompton box motion comprising a constantly rotating master gear having a plurality of segments of gear teeth which are brought into contact with box lever actuating pinions by means of sliding teeth, as set 20 forth in Patent No. 364,697.

With these and other objects in view which will appear as the description proceeds, my invention resides in the combination and arrangement of parts hereinafter 25 described and set forth in the claims.

In the accompanying drawings wherein I have shown a convenient embodiment of my invention,

Fig. 1 is a side elevation of a loom showing 30 the box motion pattern mechanism with my invention applied thereto,

Fig. 2 is a top plan view looking in the direction of arrow 2, Fig. 1 and showing the levers which are controlled by the pattern 35 chain and the multiplier,

Fig. 3 is an enlarged partly vertical and partly diagonal section on line 3—3 of Fig. 1, my invention in this figure being shown inoperative to permit the box motion to be 40 used in the usual manner,

Fig. 4 is a top plan of the box motion,

Fig. 5 is a view similar to a portion of Fig. 3 but showing my invention in position to permit the weaving of crepe or other 45 patterns calling for colors in alternating pairs of picks,

Fig. 6 is a vertical section on line 6—6 of Fig. 3, and

Fig. 7 is a detail vertical section on line 50 7—7 of Fig. 5.

Referring more particularly to Fig. 1 it will be seen that I have provided a loom frame 10, lay 11, shuttle boxes 12, box rod 13, and yielding lifter 14 connected to box 55 lever 15, all of the usual construction. Said lever is pivoted as at 16 on a shorter lever 17 pivoted at 18 on the box motion stand 19.

The loom is provided with the usual bottom shaft 20 having keyed thereto a master 60 gear 21 provided with spaced segments of gear teeth 22 and 23. The box frame 19 has secured therein a pair of studs 24 each having pivotally mounted thereon a support 25 in the upper part of which is rotatably 65 mounted a short shaft 26. The shafts have

secured thereto crank plates 27 which are pivotally connected by means of studs 28 to links 29, the studs 28 being eccentric with respect to the shafts so that as the latter rotate the links 29 will be raised and lowered. 70

The parts carried by the support 25 are substantially the same and a description of one will suffice for both.

The front shaft 26 has a pinion 30 secured thereto by key 31 as shown in Fig. 7. Said pinion is provided with oppositely disposed slots 32 which receive the long and short arms 33 and 34, respectively, of a sliding member 35 which is grooved as at 36 to receive the actuating finger 37 of a control lever 38. The arm 33 is provided at its extremity with a starting tooth 39 while the shorter arm 34 is provided near its extremity with a similar starting tooth 40. The control lever 38 is actuated by connector 41 which is connected to pattern lever 42 pivoted to a fixed stud 43 as shown in Figs. 1 and 2.

The pattern lever 42 is raised and lowered by a pattern chain 45 mounted on a cylinder 46 keyed to a short shaft 47, see Figs. 1 and 2. A clutch member 48 is fastened to shaft 47 and has notches to cooperate with a tooth 49 on a clutch member 50 slidable along shaft 47. Said member 50 has a groove 51 to receive the end 52 of a lever pivoted at 53 and having an arm 54 which lies over the multiplier chain 55. The multiplier chain is mounted on a cylinder 56 keyed to a second short shaft 57 which has secured thereto a clutch member 58 similar to member 48. A second clutch member 59 is mounted to slide along shaft 57 and has a tooth 60 to cooperate with notches in member 58. Said member 59 is grooved as at 61 to receive end 62 of a lever 63 which is pivoted at 64 and has an end 65 to extend over one section of the pattern chain 45. The shafts 47 and 57, together with levers 54 and 63 are mounted on a stand 66 supported by the loom frame. 110

As shown in Fig. 2 an upright shaft 67, constantly driven by mechanism not shown, has keyed thereto a worm 68 which meshes with worm gears 69 and 70 turning loosely on shafts 47 and 57, respectively. The worm gears 69 and 70 are driven on sleeves 71 and 72, respectively, said sleeves having cast integral therewith collars 73 and 74, respectively, which guide the teeth 49 and 60. The worm is formed with a dwell so that one of the worm gears is at rest while the other is being turned by the worm. The pattern and multiplier chain mechanisms just described are similar in construction and operation to those found in Patent No. 656,592 125 to Wyman. It is sufficient for present purposes to state that pattern cylinder 46 will be brought to rest when end 65 of lever 63 is raised by a ball on pattern chain 45 and that multiplier chain 55 will thereafter be- 130

gin to move and lower lever 54, in this way disengaging tooth 49 from clutch member 48 to arrest the pattern chain. When the multiplier chain has made a complete revolution, or when another ball arrives under lever 54, the pattern chain will again begin to move. In this way the levers over the pattern chain remain at rest while the multiplier chain operates.

10 In the operation of the device so far described the pattern chain will receive a movement for each second pick of the loom and will raise or lower the lever 42 according to the demands of the pattern. The starting teeth 39 and 40 are so related with respect to the segment 23 that but one of the starting teeth will be in operative position with respect to the master gear 21, the tooth 39 being shown in alignment with the segment 23 in Fig. 3 while the tooth 40 is out of the plane of the segment. In order to effect a change from the position shown in Fig. 3 the control lever 38 would be raised whereupon tooth 39 would move out of position 25 and tooth 40 would move into position with respect to segment 23 and as the master gear rotates said segment 23 would engage the starting tooth 40 and give the pinion 30 a half revolution at the conclusion of which 30 the starting tooth 40 would be diametrically opposite the bottom shaft 20. When a return to the position shown in Fig. 3 is desired the control lever 38 will be depressed and the tooth 39 which was moved to a position 35 between the bottom shaft 20 and the shaft 26 by which it is supported will be in operative position with respect to the segment 23.

It is to be understood that each segment 40 controls one of the pinions and that as the latter rotate their links 29 will be raised or lowered so as to give the box lever 15 four different positions. Locking levers 75 co-operate with the crank plates 27 to lock the latter, said locking levers being held down by springs 76 and being pivoted on fixed studs 77. The matter thus far described is a common form of the well-known Crompton box motion and so-called cylinder motion 45 and forms no part of my present invention, the same being constructed and operating substantially the same as the motion set forth in Patents Nos. 364,697 and 656,592 aforementioned.

50 In carrying out my invention I provide the support 25 which carries the pinion and shaft previously described with a reduced sleeve 80 on which is slidably mounted an auxiliary member 81 grooved as at 82 to receive the controlling finger 83 of a control lever 84 pivoted on a fixed stud 85. The horizontal arm of said lever 84 is connected to a lifting rod 86 which is in turn connected to pattern lever 87 pivoted on the 55 stud 43.

Said member 81 is provided with a starting tooth 88 formed on an arm 89 which is guided in the slot 32 opposite the arm 33. Said starting tooth 88 is substantially similar to starting tooth 39 and when moved to 70 the left from the position shown in Fig. 3 will lie in the path of the leading tooth of the segment 23.

In the operation of my invention the tooth 88 will remain in the position shown in Fig. 75 3 so long as the pattern calls for relatively broad stripes or a solid block of color but when the weave is to change so as to call the alternate pairs of picks of different colors the pattern chain 45 will lift the lever 87 against the action of coil spring 90 one end of which is connected to the lever 84 and the other end of which passes through stud 85. The pattern chain 45 is built so as to call the multiplier chain at this time and the pattern chain will therefore come to rest as previously explained. This will leave both the starting teeth 39 and 88 in the plane of segment 23 as shown in Fig. 5 and will leave starting tooth 88 in position to be engaged by the leading tooth of segment 23. As the master gear 21 rotates the segment will engage tooth 88 and give the pinion 30 a half revolution and since all the teeth of segment 23 are required for this movement tooth 39 will be left in position to engage the segment 23 on the next revolution of the master gear 21. So long as tooth 88 is in the position shown in Fig. 5, therefore, the pinion 30 will be given a half rotation every alternate pick of the loom. For this reason the link 29 actuated by the pinion 30 will remain up for two picks and then will be lowered for two picks and will then again be raised for two picks, this sequence prevailing so long as it is desired to weave a pattern having alternate pairs of picks of different kinds. When it is desired to return to the other part of the repeat the multiplier will start 100 the pattern chain so as to lower the lever 87 and permit spring 90 to move the tooth 88 out of the plane of the segment 23.

I have shown herein a box motion having two pinions and two segments on the master gear to operate four boxes on one side of the loom but it is well known that a box motion of this type can be employed to control four boxes where two of them are on one side of the loom and two on the other 115 and I do not wish to be limited to the showing herein where all of the boxes are on one side of the loom.

As shown in Fig. 6 I have rendered each of the supports 25 and shafts 26 yieldable about their studs 24 by providing a tension spring 91 held at one end by a notch 92 formed in the upper end of one of the levers 25 and held at the other end by an eye bolt 93 secured adjustably in the upper end of 120 125 130

the other lever 25. In this way should the auxiliary tooth 88 be improperly positioned as it slides from the position shown in Fig. 3 to that shown in Fig. 5 the parts may move 5 outwardly under the action of spring 91 to prevent breakage.

It will be seen that by the structure set forth herein it is possible to control the starting pinion from either of two pattern 10 levers, the lever 87 being additional to the usual lever 42. In this way the designer of the fabric has a choice of two spaces on a pattern chain to control the starting teeth of one pinion. Such a control makes it possible 15 to build the chain which controls the levers 42 for producing a solid block of color and then to introduce narrow stripes of a different color by lifting lever 87 at selected intervals. A chain so built makes it possible 20 by having the connections as shown between lever 87 and the starting teeth to weave with the stripe, but if the stripe is to be omitted and all other parts of the pattern remain the same the connector 86 may be 25 detached from the lever 87 so as the latter rises it will be ineffective to move the auxiliary starting tooth.

From the foregoing it will be seen that I have applied an auxiliary sliding tooth to 30 the well-known Crompton box motion in such a way as to permit the weaving of crepes and other fabrics calling for alternate pairs of picks of different wefts by the use of a multiplier, the auxiliary tooth 35 operating with one of the segments of the ordinary master gear and being guided by a slot in the pinion which usually receives the short arm of the sliding member 35. It will further be seen that the device lends 40 itself naturally to use with the ordinary form of slide 35 in that the shorter arm provides room for the auxiliary tooth 88 in such position that the latter will be diametrically opposite the leading tooth 39 of the longer arm. It will further be seen that 45 should the auxiliary tooth be improperly placed with respect to the segment provided therefor the parts can yield to prevent breakage.

Having thus described my invention it will be apparent that changes and modifications may be made therein by those skilled in the art without departing from the spirit and scope of the invention, and I do not 55 wish to be limited to the details herein disclosed, but what I claim is:

1. In a box controlling mechanism for looms having a set of shifting boxes and a box lever to control the position of the 60 boxes, a member having a regular movement in a plane of action and completing its cycle of movement every second pick of the loom, a pinion to cooperate with the member and operatively connected to the lever to move 65 the latter when said pinion receives an an-

gular movement, sliding starting teeth for the pinion located on diametrically opposite sides thereof, each tooth being movable into operative position with respect to the member having a regular movement, and pattern controlled means to move and hold both of said members in the plane of the rotating member at the same time. 70

2. In a box controlling mechanism for looms having a set of shifting boxes and a box lever to control the position of the boxes, a regularly rotating master gear having a segment of gear teeth moving in a plane of action and making a complete revolution every second pick of the loom, a pinion operatively connected to the box lever, a pair of starting teeth for the pinion located on diametrically opposite sides thereof, each of said teeth being movable into the plane of action of the segment, and pattern controlled means to move both of said starting teeth in the plane of the segment at the same time to cause said pinion to have a half revolution for each complete revolution of the segment, whereby the box lever will be changed every second pick of the loom while said teeth remain in the same relative position with respect to the pinion. 80

3. In a box controlling mechanism for looms having a set of shifting boxes and a box lever to control the position of the boxes, a segment of gear teeth moving in a plane of action and making a complete revolution every second pick of the loom, a pinion to co-act therewith, connections between the pinion and the lever to move the latter when the pinion is given an angular movement, a pair of starting teeth located on opposite sides of the pinion, pattern mechanism to control the starting teeth, said teeth remaining in the same position relatively to the pinion when said pattern mechanism is at rest, and connections between the pattern mechanism and the teeth to move both of said teeth into the plane of action of the segment at the same time to cause said pinion to have a half revolution for each complete revolution of the segment, whereby the box lever will be given a box changing movement every second pick of the loom while the pattern mechanism is at rest. 100

4. In a box controlling mechanism for looms having a set of shifting boxes and a box lever to control the position of the boxes, a segment of gear teeth moving in a plane of action and making a complete revolution every second pick of the loom, a pinion to be operatively related to the segment, a pair of starting teeth for the pinion independently movable into operative position relatively to the segment and with respect to each other, pattern mechanism to control the teeth, and connections from the pattern mechanism to the teeth to move both of the teeth into the plane of action of the seg- 110

ment at the same time to cause said pinion to have a half revolution each second pick of the loom, whereby the box lever will be given a box changing movement every other 5 pick of the loom so long as the pattern mechanism holds the teeth in the plane of action of the teeth of the segment.

5. In a box controlling mechanism for 10 looms having a set of shifting boxes and a box lever to control the position of the boxes, a constantly rotating segment of gear teeth moving in a plane of action and making a complete revolution every second pick of the loom, a pinion operatively connected 15 to the box lever and actuatable by the segment, a pair of independently movable starting teeth for the pinion and oppositely disposed with respect to the pinion and each movable into the plane of action of the segment, pattern 20 mechanism to move both of said teeth in the plane of action of the segment at the same time to cause said pinion to have a box lever moving motion every second pick of the loom while the pattern mechanism maintains 25 both the teeth in the said plane of action, and multiplying mechanism for the pattern mechanism to determine the number of picks during which both of said teeth shall remain in the plane of action of said 30 segment.

6. In a box controlling mechanism for looms having a set of shifting boxes and a box lever to control the position of the boxes, a constantly rotating segment of gear teeth 35 moving in a plane of action and having a complete cycle of movement in an even number of picks, a pinion operatively connected to the box lever and actuatable by the segment, two regular starting teeth for the pinion lying in different planes with respect to the plane of the pinion and movable together, said teeth lying on opposite sides of the pinion, and an auxiliary starting tooth for the pinion movable independently of the first 45 named teeth and movable into the plane of one of said regular teeth, pattern mechanism to control the position of all of said teeth, connections between the pattern mechanism and the teeth to move the auxiliary tooth 50 and one of the regular teeth into the plane of action of the segment to cause a half revolution of the pinion for each complete revolution of the segment, said auxiliary tooth being movable out of the plane of 55 action of the segment and the other of said regular teeth being movable into the plane of action of the segment, whereby said box lever can be given a box shifting movement for each revolution of the segment when one 60 portion of the pattern mechanism is in control, the box lever having a different sequence of movements when another portion of the pattern mechanism is in control to move said other of the regular teeth into the 65 plane of action of the segment.

7. In a box motion for looms having shifting boxes and a box lifting lever operatively connected thereto, a regularly moving segment of gear teeth moving in a plane of action and having a complete revolution in 70 an even number of picks, a pinion operatively connected to the box lever and actuatable by the segment, two separate starting devices independently movable with respect to each other to initiate movement of the pinion by 75 the segment, the first of said devices comprising two starting teeth which lie in different planes with respect to the plane of the segment, and the other device comprising a single tooth, and pattern mechanism to move the first named device independently of the second named device and also to move said second named device and one of the teeth of the first named device into the plane of action of the segment to cause a half 80 revolution of the pinion for each pick of the loom, whereby the box lever will shift the boxes every time said segment has a complete revolution.

8. In a box motion for looms having shifting boxes and a box lifting lever operatively connected thereto, a regularly moving segment of gear teeth moving in a plane of action and having a complete revolution in 85 an even number of picks, a pinion operatively connected to the box lever and actuatable by the segment, two separate starting devices independently movable with respect to each other to initiate movement of the pinion by 90 the segment, the first of said devices comprising two starting teeth which lie in different planes with respect to the plane of the segment, and the other device comprising a single tooth, pattern mechanism to move the first named device independently of the second named device and also to move said second named device and one of the teeth of the first named device into the plane of action of the segment to cause a half 95 revolution of the pinion for each pick of the loom, whereby the box lever will shift the boxes every time said segment has a complete revolution.

9. In a box motion for looms having a set of shifting boxes and a box lever to control the position thereof, a constantly rotating segment of gear teeth moving in a plane of action and making a complete revolution every second pick of the loom, a pinion operatively connected to the box lever and actuatable by the segment, a pair of starting devices for the pinion to initiate movement thereof by the segment, the first of said devices comprising a long and a short arm each provided with a starting tooth, said starting teeth lying in different planes with 100 105 110 115 120 125 130

respect to the plane of action of the segment, said arms lying on opposite sides of the pinion, said second starting device comprising a tooth lying on the same side of the 5 pinion with the short arm, and pattern mechanism to move the tooth on the long arm of the first named device and the tooth on the second named device both into the plane of action of the segment at the 10 same time to cause said pinion to have a half revolution for each second pick of the loom, whereby the box lever is given a box shifting movement every other pick of the loom while said starting teeth retain 15 the same relative position with regard to the plane of action of the segment.

10. In a box motion for looms having a plurality of shifting shuttles and a box lever to control the position of the same, a constantly 20 rotating segment of gear teeth moving in a plane of action and having a complete revolution every second pick of the loom, a pinion operatively connected to the box lever and actuatable by the segment, two 25 independently movable starting devices associated with the pinion and movable into operative relation with respect to the segment to initiate angular movement of the pinion, one of said devices having two starting 30 teeth lying on opposite sides of the pinion and in different planes with respect to the plane of the pinion and the other starting device having a single starting tooth, pattern mechanism to control the 35 position of the first named device, connections from the pattern mechanism to the second device to move the tooth thereof into the plane of action of the segment when one of the teeth of the first named device 40 is in the plane of action of the segment, and multiplying mechanism controlling the pattern mechanism to determine the number of picks during which the starting tooth of the second named device shall lie in the plane of 45 action of said segment, the starting tooth of the second device when in the plane of the segment cooperating with one of the teeth of the first named device to give the pinion an operative movement every second pick of 50 the loom to cause the box lever to initiate the boxes every other pick of the loom.

11. In a box motion for looms having shifting shuttle boxes and a pattern chain, a master gear rotating in a fixed plane, a 55 sliding member forming part of the box motion and having starting teeth out of alignment with respect to each other relatively to the plane of movement of the master gear so that but one starting tooth 60 may be operatively related to the master gear at a time, connections between the pattern chain and sliding member to determine the position of the latter, and an auxiliary sliding element also forming part of the 65 box motion and having a starting tooth mov-

able into the plane of action of the master gear when one of the first named starting teeth is in the plane of action of the master gear, whereby both starting teeth may be engaged by the master gear while the pattern chain is at rest. 70

12. In a box motion for looms having shifting shuttle boxes and a pattern chain, a master gear moving in a fixed plane of rotation, a pair of starting teeth under control of the pattern chain movable across the plane of action of the master gear and being out of line with each other so that but one starting tooth may be operatively related at a time to the master gear, and a third starting tooth movable independently of the first named starting teeth to be moved into the plane of action of the master gear when one of said pair of starting teeth is also in the plane of action, whereby both starting teeth 80 will be actuated by the master gear while the pattern chain is at rest. 85

13. In a box motion for looms having shifting shuttle boxes and a pattern chain, a master gear moving in a fixed plane of rotation, a pair of starting teeth fixed with respect to each other and under control of the pattern chain to be moved transversely of the plane of action of the master gear so that either of said pair of starting teeth 90 may be operative one at a time with respect to the master gear, and a third starting tooth movable independently of the first two starting teeth into and out of the plane of action of the master gear, said third starting tooth 95 and one of the pair of starting teeth first named being capable of both lying in the plane of action of the master gear to be alternately actuated by the later while the pattern chain is at rest. 100

14. In a box motion for looms having shifting shuttle boxes and a pattern chain, a master gear moving in a fixed plane of action, a pinion connected to the box motion, a pair of members having sliding engagement with the pinion and movable transversely of the plane of action of the master gear, one of said members having a pair of starting teeth lying on opposite sides of the pinion and out of alignment with respect to each other relatively to the plane of the master gear and the other member having a starting tooth opposite one of the pair of teeth relatively to the axis of the pinion, and a pattern chain lever for each member, said levers capable of moving two diametrically opposite starting teeth into the plane of action of the master gear to cause continued rotation of the pinion by the master gear while the pattern chain is at rest. 110 115 120

15. In a loom box motion, a pattern chain, a pair of pattern levers each to be operated independently of the other by the chain, an actuating member, a pinion to be operated by the member and forming part of the box 125 130

motion, and means operatively related to the pinion and controlled by the levers whereby either lever may control said pinion to cause operative relation thereof with the actuating member.

16. In a box motion for a loom having a pattern chain, an actuating member, a pinion forming part of the box motion, two sliding starting teeth for the pinion mov-

able relatively to each other, and a pattern

lever for each starting tooth, said pattern levers being controlled independently of each other by the pattern chain, either pattern lever being capable of moving the starting tooth corresponding thereto into the path of the actuator to cause movement of the pinion by the actuator member.

In testimony whereof I have hereunto affixed my signature.

ALBERT A. GORDON.
